United States Patent Office

Des. 181,727
Patented Dec. 17, 1957

181,727

COMBINATION BENCH AND TABLE

William J. Haynes, Sr., Lake Forest,
Bonner Springs, Kans.

Application June 11, 1956, Serial No. 41,834

Term of patent 14 years

(Cl. D15—11)

Fig. 1.

Fig. 2.

Fig. 1 is a perspective view of the combination bench and table shown in condition for use as a bench, showing my new design.

Fig. 2 is a perspective view thereof shown in condition for use as a bench and a table.

I claim:

The ornamental design for a combination bench and table, as shown.
